UNITED STATES PATENT OFFICE.

MAX G. PAULUS AND OSWALD C. BREWSTER, OF CASPER, WYOMING, ASSIGNEES TO
STANDARD OIL COMPANY, OF WHITING, INDIANA, AND CHICAGO, ILLINOIS, A COR-
PORATION OF INDIANA.

APPARATUS FOR THE DISTILLATION OF HYDROCARBON OILS.

Application filed February 27, 1924. Serial No. 695,459.

The present invention relates to improvements in the fractional distillation of hydrocarbon oils, and will be clearly understood from the following description, illustrated by the accompanying drawings, in which:

Figure 1 is a diagrammatic view, partly in section, showing an arrangement of devices for carrying the present invention into effect;

Fig. 2 is a transverse sectional view through fractionating column shown in Fig. 1, on the line 2—2 of Fig. 3; and

Fig. 3 is a broken transverse section of a portion of the fractionating column.

Referring more particularly to the drawings, the numeral 5 indicates a portion of a still in which the material to be fractionated is charged. This material may suitably be crude petroleum or a fraction thereof, for example, a naphtha distillate containing both gasoline and kerosene fractions. From the still 5 a vapor line 6 leads to a fractionating column 7 suitably formed of a number of superimposed sections, the construction of which will be more fully hereinafter set forth. From the column 7 a vapor line 8 leads the vapors to a vapor manifold or header 9. From this vapor manifold 9 a suitable number of branch lines (designated as 10, 11, 12 and 13) lead to condenser worms 14 in a condenser box 15. From these worms lines 16, 17, 18 and 19 lead to a manifold 20 provided with valves 21 for controlling the flow of the condensates from the several worms. From the manifold 21 a reflux line 22 leads back to the column 7 and another line 23 leads to a suitable receiving drum 24.

The construction of the tower 7 is shown in Figs. 2 and 3. The column 7 is divided into a number of superimposed sections 7* by the transverse partitions 26, each of which is provided with a central opening 27 around which is a cylindrical wall or riser 28. A rotatable shaft 29 passes centrally through the openings 27 in the partitions 26, being mounted in a step bearing not shown in the base of the tower and extending upwardly through a stuffing box 31 in the top of the column, for connection in any desired manner with a driving means, for example, an electric motor. Secured to the shaft 29 above the transverse partitions 26 is a cap or bell 33, having a suspended cylindrical

skirt 34 surrounding the cylindrical riser or wall 28 and dipping below the level of the liquid on the partitions 26, maintained by the riser 28 and the overflow pipes hereinafter referred to. The lower portion of this cylindrical skirt 34 is slotted vertically, and the slit portions are bent inwardly and forwardly (relative to the direction of movement of the cap or bell) thereby forming openings 35 and forwardly directed vanes 36. On rotation of the shaft and of the bells 33 or caps 33 in the direction indicated by the arrow in Fig. 2, it is readily apparent the vanes 36 will tend to cause an outward movement of the liquid present on the transverse partition 26 as well as impart to it a whirling or rotary movement.

Surrounding the central cylindrical riser 28 is a stationary baffle pan 37 having a central opening somewhat larger than the cylindrical riser 28. This baffle pan may suitably rest upon small lugs or projections 38, which raise it slightly above the transverse partition 26, permitting flow of liquid therebetween. The walls of the baffle cup 37, which may suitably be cylindrical in form, extend upwardly not quite to the top of the cap or bell 33, and are then turned inwardly, extending almost to the skirt 34 of the cap. This inwardly turned portion or cover portion of the baffle pan 37, designated by the numeral 39, is slotted and bent to form downwardly directed vanes 40. At intervals in the base of the side wall of the baffle pan 37, openings 41 are provided, from one side of which extend outwardly the projecting lugs 42. An overflow pipe 43 extends from a suitable distance above each of the transverse partitions 26 through the latter and downwardly to near the upper surface of the next lower partition, terminating within a cup formed by a curved vertically disposed plate 44, which rests upon the upper surface of the transverse partition 26 and may suitably be secured to the baffle pan 37.

Under operating conditions, the still 5 is suitably heated, either by direct fire or by the injection of steam or both, and the vapors passing therefrom enter the fractionating column 7. Within the column 7 a layer of liquid is maintained on each of the transverse partitions 26, the height of this layer being determined by the height of the over-

flow pipe 43. Vapors rise through the central openings 27 in the transverse partitions 26. The bells or caps 33 force the vapors down into contact with the liquid, and by 5 their rotation, cause a thorough intermingling of liquid and vapors. The rotation of the bells 33 produces a whirling movement of the liquid on the transverse partitions 26 and, by the action of the openings 35 and 10 vanes 36, also causes an outward movement of the liquid. The liquid is thus whirled about within the baffle pan 37 and, at the same time, driven outwardly toward the walls of the latter. The tendency of the liquid 15 to form vortices is checked by the downwardly projecting vanes 40 formed in the top or cover portion of the baffle pan 37. The outward movement of the liquid causes it to pass outwardly through the openings 41 20 in the side walls of the baffle pan 37 and it returns to the interior of the bell or cup 33, in which there is a reduced pressure, through the space between the bottom of the baffle pan 37 and the upper surface of the trans- 25 verse partition 26. Thus a continuous circulation of the reflux liquid, as well as a rotary movement causing thorough intermixture between vapor and mixture, is produced. From the bottom of the column 7, 30 reflux liquid returns to the still through the vapor line 6.

From the top of the column vapors pass out through the vapor line 8 to the manifold 9, and portions thereof pass through each 35 of the vapor lines 10, 11, 12 and 13 to the corresponding condensing worms 14 and the condensate lines 16, 17, 18 and 19. The branch vapor lines 10, 11, 12 and 13 are each valved, the passage of vapors therethrough 40 being hence controllable.

By means of the control valves 21, the condensates passing through the lines 16, 17, 18 and 19 may, at will be directed to the receiving tank 24, or may be returned through 45 the runback line 22 to the baffle pan of the tower or column 7. In normal operation, the condensate from one or more of the branch vapor lines above described is returned to the reflux column.

50 We claim:

1. In a fractionating column, a transverse partition having a vapor passage therethrough, means for retaining a body of liquid on said partition, a cap over said vapor opening, said cap having an opening beneath the liquid level, means for rotating said cap, and means exterior to said cap for preventing formation of vortices in the liquid.

60 2. A fractionating column having a transverse partition, said partition being pro-

vided with a vapor passage, means for retaining a body of liquid on the transverse partition, a cap over said vapor passage and extending below the liquid level, lateral 65 openings in the walls of said cap below the liquid level, and stationary means having vane-like members located outwardly of the side walls of the cap and curving downwardly toward the transverse partition; said 70 means tending to break vortices formed by rotation of the cap.

3. A fractionating column having transverse partitions provided with vapor passages, means for retaining a liquid body on 75 said transverse partitions, caps surmounting the vapor passages and extending downwardly below the liquid level, said caps being provided with lateral openings below the level of the liquid and inwardly directed 80 vanes at said openings, baffle pans surrounding said caps and having their bottoms spaced from the top of the transverse partitions, lateral openings being provided in said baffle pans, and means for rotating said 85 caps whereby a circulation of the liquid through the openings in the baffle pans and back below said baffle pans is produced.

4. A fractionating column having transverse partitions, means for maintaining 90 bodies of liquid on said partitions, vapor passages through said partitions, caps surmounting said vapor passages and extending downwardly below the liquid level thereon, said caps being provided below the level of 95 the liquid with lateral openings and vanes at said openings, stationary baffle pans surrounding said caps, said pans having bottom portions spaced above the transverse partitions, the side walls of said baffle pans being provided with openings, and a cover portion 100 formed on said baffle pan, said covered portion being provided with downwardly directed members, and means for rotating the caps.

105 5. The combination with a still, of a fractionating column, a vapor line leading from said column, a plurality of branch vapor lines leading from said vapor line, means for condensing vapors passing through said 110 branch vapor lines, a manifold communicating with said branch vapor lines at their lower extremities, a liquid return pipe from said manifold to said fractionating column and valves in said manifold between said 115 branch vapor lines, whereby a part of the condensate from said vapor lines may be caused to flow by gravity through said liquid return pipe to the column.
